UNITED STATES PATENT OFFICE.

MILLS L. CALLENDER, OF NEW YORK, N. Y.

IMPROVEMENT IN HYDROCARBON-BURNERS.

Specification forming part of Letters Patent No. 38,031, dated March 31, 1863.

To all whom it may concern:

Be it known that I, MILLS L. CALLENDER, of New York, in the county and State of New York, have made certain Improvements in Hydrocarbon-Burners; and I do hereby declare that the following is a full and exact description thereof, reference being had to the accompanying drawings, and to the letters of reference marked thereon.

The nature of my invention consists in providing hydrocarbon-burners with appliances by which the heat of the illuminating-flame is prevented from being communicated to the wick-tube and oil-receptacle, and by which the burner will burn hydrocarbon oils with a clean, smokeless flame, either with or without a glass chimney.

To enable others skilled in the art to make and use my invention, I will proceed to describe its construction and operation.

The dome *b* of the deflector *A*, as shown in Figure I of the accompanying drawings, is formed of metal, and is provided with the flame-slot *c*. The heat communicated to the dome *b* by the flame is confined entirely in the said dome *b* by the mica cylinder *d*, which is secured firmly to the dome *b*, and to the base *f* of the deflector *A*, by means of the flat conformed rings *g g* and *h h*. The top of the mica cylinder *d* being clasped between the outer surface of the dome *b* and the inner surface of the flat conformed ring *g g*, and firmly secured in this position by punching a portion of the metal of the flat conformed ring *g g*, through the top of the mica cylinder *d*, into the metal forming the lower part of the dome *b*, as represented by the dots *p p p* in Fig. I of the accompanying drawings, the bottom of the mica cylinder *d* is clasped between a metallic flange, rising from the base *f* of the deflector *A*, and the interior surface of the flat conformed ring *h h*, and firmly secured by punching a portion of the metal of the flat conformed ring *h h* through the bottom part of the mica cylinder *d* into the metallic flange rising from the base *f* of the deflector *A*, as represented by the

dots *s s s* in Fig. I of the accompanying drawings. The mica cylinder *d* is thus firmly held between the dome *b* and the base *f*, and thus completely confines the heat imparted by the flame to the dome *b* of the deflector *A*.

The wick-tube *J* of the burner *K*, as shown in Fig. II of the accompanying drawings, is provided with the interior adjustable metallic and mica deflector *m*, (shown in Fig. III of the accompanying drawings,) the deflector being so arranged that the flat surfaces of the mica shields *o o* are presented to the sides of the flame, causing currents of air to be impelled in close proximity to the sides of the flame without imparting heat to the wick-tube *J*. The mica shields *o o* are movable, and can be changed or renewed at pleasure. By elevating the interior adjustable metallic and mica deflector *m*, the burner can be used without a chimney, and by again depressing it a chimney can be applied and the burner used as the ordinary chimney-burner, with the great advantage of not communicating the heat of the flame to any portion of the burner or lamp, below the metallic dome *b* of the cone *A*.

What I claim as my invention, and desire to secure by Letters Patent, is—

1. An improved lamp-deflector composed of a combination of mica and metal, consisting of a metallic base ring or flange, *f*, the mica or similar non-conducting cylinder *d*, and insulated dome *b*, constructed as above set forth.

2. The use of a mica, glass, or similar non-conducting cylinder, when applied to a lamp-top for the purposes above specified.

3. The method of securing the mica to the metal, as above specified.

4. Constructing the interior adjustable cone *m* of a combination of mica and metal, as above set forth.

MILLS L. CALLENDER.
